(Continued)*Primary Examiner* — Michael Pratt(74) *Attorney, Agent, or Firm* — Barlow, Josephs & Holmes, Ltd.(57) **CLAIM**

The ornamental design for a fixed sight aperture, as shown and described.

DESCRIPTION

FIG. 1 is a perspective view of a fixed sight aperture in accordance with the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of portions of the fixed aperture sight is included for the purpose of illustrating environment and forms no part of the claimed design.
